ATTORNEY

UNITED STATES PATENT OFFICE.

HUGH T. HUGHES, OF CLEVELAND, OHIO, ASSIGNOR OF ONE-HALF TO ALBERT CROST,
OF CLEVELAND, OHIO.

RUBBER HEEL.

Application filed October 24, 1922. Serial No. 596,585.

To all whom it may concern:

Be it known that I, HUGH T. HUGHES, a citizen of the United States, and resident of Cleveland, in the county of Cuyahoga and State of Ohio, have invented certain new and useful Improvements in Rubber Heels, of which I hereby declare the following to be a full, clear, and exact description, such as will enable others skilled in the art 10 to which it appertains to make and use the same.

The objects of the invention are to provide an improved form of cushion heel or elastic lift for a leather heel having the following characteristics.

It includes a lift having its inner surface concaved transversely, and broken by a multiple member of concentric ridges separated by grooves which however do not 20 emerge at the sides or ends of the lift but are terminated by marginal walls, in such a manner as to form suction pockets or vacuum cups, tending to retain the lift in its place.

25 The ribs separating these corrugations may have vertical or inclined sides and are so arranged that the nails may be driven through any of them, at any desired distance from the margin of the lift thus enabling the shoemaker to cut off any amount 30 of the margin necessary to fit the rubber heel to any desired size of leather heel, and enabling him to reduce the amount of stock kept on hand.

35 In this construction when the edges are drawn flat against the heel they cannot be pulled down, and separated from the body of the heel.

Also the grooves tend to make the heel 40 more resilient under foot than if the substance of the lift were solid throughout. Also the nails are held in place by means of a wire netting which permits the lift to be evenly drawn flat, and one nail will hold 45 the lift in place until other nails can be driven.

The invention is hereinafter more fully described shown in the accompanying drawings and specifically pointed out in the 50 claims.

In the accompanying drawings Fig. 1 is a plan of the lower face of the lift. Fig. 2 is a transverse section thereof. Fig. 3 is a longitudinal section thereof. Fig. 4 is a 55 transverse section and shows a concaved

form; Fig. 5 is a transverse section of a modified form of rib; Fig. 6 is a plan, showing a fewer number of ridges; Fig. 7 illustrates a tapered heel.

In these views, A represents a lift formed 60 of rubber or resilient composition, the lower surface of which is provided with concentric ridges, B, B, alternating with grooves, B', B', which terminate in at the front wall, C, the upper surface of which is level with 65 the heel.

The sides of these grooves are preferably 70 inclined as at D, D, on the inner side, and vertical as at E, on the outer side, and the ridges are preferably terminated by flat surfaces, F, F, and a central longitudinal ridge is provided, with a flat surface, F'. These 75 surfaces are drawn tightly against the bottom of the heel by means of nails inserted through the ridges. The grooves between the ridges then become air pockets which serve to cushion the weight upon the heel and relieve the foot and ankle of the wearer from shock when the lift is nailed in place. When nails are driven through the central 80 longitudinal rib, the rib serves as an abutment preventing the collapse or further compression of the heel that would take place if the cavity should extend past the center of the heel.

A wire netting, G, is employed to prevent 85 the lift from slipping over the heads of the nails driven in the openings, H, and has the advantage that a single nail centrally driven will hold the entire lift closely in 90 place and until the other nails can be driven, thus being much more efficient than washers.

The bottom of the heel may be flat, as 95 shown in Figures 3, 2 and 5, but may be crowned in one or both directions, as shown in Figures 4 and 5, if desired.

The heel may be tapered from the rear edge to the front, as shown in Figures 3 and 7, thus increasing its wearing quality, 100 since the rear end is the first to become worn. Also it eliminates the necessity of inserting additional lifts. This makes the rear end of the heel higher and on a level with the ball of the foot.

The solid level center supports the weight 105 and prevents the edges from collapsing and the wall, C, across the rear retains the pockets in shape and prevents the admission of air into the grooves. The thin marginal

edges, when pressed down upon the leather heel, remain tight and prevent dirt from entering, and do not separate from the leather.

5 In Figs. 4 and 5 the heel is shown having a general concavity in one transverse direction only. This insures a perfect fit upon the leather heel.

10 The raised or inclined edges, F, and F', of the ridges, receive the nails and thus permit the outer edge to be pared off by the shoemaker from ridge to ridge to fit heels of different sizes, and the ridges are so spaced as to permit such action. For this reason, a 15 fewer number of heels can be kept in stock, one heel serving for several sizes of heels.

20 When intermediate sizes are desired the nails can be driven through the inclined sides and a fibre washer perforated for nail holes can be employed which can be cut when paring the sides of the heel.

25 In Fig. 7 a heel tapered to give increased thickness in the rear at A' is shown in connection with a smooth upper edge and longitudinal openings B' which are deepest in the rear to give increased resiliency to the thick portion.

The openings taper upward at B² in front.

30 Having described the invention, what I claim as new and desire to secure by Letters Patent is:

1. In a rubber heel, a body having its upper surface provided with a marginal ridge, on its sides and rear end, and a transverse ridge on its front end, and with inner ridges parallel with the sides and rear end thereof, and terminating in said transverse front ridge, and with grooves between said side and rear ridges, said side and rear

ridges having sloping inner faces, and the bottoms of said grooves sloping upwardly towards said front ridge, said ridges being spaced apart to permit division of said heel into different sizes. 40

2. In a rubber heel, a trough shaped body 45 having its upper surface provided with a marginal ridge, and with alternating grooves and ridges parallel therewith, and arranged about three sides thereof, and also provided with a front transverse wall closing the front extremities of said grooves, the central one of said ridges being longitudinal of said heel, the outer faces of said ridges being inclined, said ridges being spaced apart to correspond with the margins of said 50 shoe of different sizes. 55

3. In a rubber heel, a body having its upper surface provided with a marginal ridge on its sides and rear end, a central longitudinal ridge, and a transverse ridge on its front end, and also provided with inner ridges parallel with the sides and rear end thereof, and terminating in said transverse front ridge, and with grooves between 60 said side and rear ridges, said side and rear ridges having sloping inner faces and the bottoms of said grooves sloping upwardly toward said front ridge, said ridges being spaced apart to permit division of said heel 65 into different sizes, said ridges being longitudinally inclined upon their upper surfaces, and said central longitudinal ridge serving to prevent the collapse of said heel when said heel is secured to the shoe. 70

In testimony whereof, I hereunto set my hand this 21st day of Oct. 1922. 75

HUGH T. HUGHES.
